UNITED STATES PATENT OFFICE.

MATTHEW WIARD AND CHARLES C. PETTIT, OF PHILADELPHIA, PA.

DESIGN FOR CARRIAGE DOOR-FENDERS.

Specification forming part of Design No. **11,243**, dated June 10, 1879; application filed April 21, 1879.
[Term of patent 3½ years.]

To all whom it may concern:

Be it known that we, MATTHEW WIARD and CHARLES COOPER PETTIT, both of Philadelphia, in the county of Philadelphia and State of Pennsylvania, have invented an Improved Design for Carriage Door-Fenders, of which the following is a specification.

Our invention relates to that class of iron-work known as "carriage door-fenders," and especially designed for stables; and consists in constructing a fender of iron or other base metal, and giving to it a shape which may represent a portion of a leg of a horse, and also in filling in the space between the leg and the wall by an ornamented or plain casting, with a flange on either side of same, which has in it lugs, through which bolts pass to secure the fender to the building.

The object of our invention is to make a carriage door-fender having a design which makes it handsome, and at the same time makes it appropriate to the use to which it is put.

Figure 1 is a perspective view of our improved carriage door-fender, in which the leg shown is that of a horse. Fig. 2 is a section of same through the line x x , Fig. 1.

Like letters of reference correspond to like parts.

A in the drawings shows a horse's leg from the knee down. B B are flanges, which rest

against the wall of the doorway, to which the fender is secured by bolts which pass through lugs C C and hole D. The space between the flanges B B and leg A is filled in with open-work E.

The bottom of the hoof has projections K K, which are secured in the ground.

There is no drilling or other expensive finishing on these castings.

We claim—

1. The design, in a carriage door-fender, of the horse's leg, in combination with the flange supplied with the slots or holes, substantially as shown.

2. The design for a carriage door-fender, consisting of the combination of the leg A, the projections K K, and the open-work E, substantially as and for the purpose specified.

3. The design for a carriage door-fender, consisting of the leg A, in combination with open-work E, flanges B B, and lugs C C, substantially as and for the purpose specified.

In testimony of which invention we hereunto set our hands.

MATTHEW WIARD.
CHARLES C. PETTIT.
